[57] CLAIM

The ornamental design for a combined lipstick and lip brush case, as shown and described.

DESCRIPTION

FIG. 1 is a perspective view of a combined lipstick holder and lip brush case showing my new design;
FIG. 2 is a top plan view thereof;

FIG. 3 is a front elevational view thereof;

FIG. 4 is a right side elevational view thereof;

FIG. 5 is a left side elevational view thereof;

FIG. 6 is a back elevational view thereof; and,

FIG. 7 is a bottom plan view thereof.

The broken line showing of the lip stick case is for illustrative purposes only and forms no part of the claimed design.

FIG. 1

FIG. 2

FIG. 4
